DESIGN FOR AN ELECTRIC BROILER

Harry Sado, New York, N. Y., assignor to Marlun
Manufacturing Company, Inc., New York, N. Y.

Application February 24, 1948, Serial No. 144,699

Term of patent 14 years

(Cl. D81—10)

To all whom it may concern:

Be it known that I, Harry Sado, a citizen of the United States of America, residing in New York city, county of New York, and State of New York, have invented a new, original, and ornamental Design for an Electric Broiler, of which the following is a specification, reference being had to the accompanying drawing, forming part thereof.

Fig. 1 is a front perspective view of an electric broiler, showing my new design.

Fig. 2 is a reduced rear elevational view.

Fig. 3 is a side elevational view thereof.

I claim:

The ornamental design for an electric broiler, substantially as shown.

HARRY SADO.
